UNITED STATES PATENT OFFICE.

HAROLD ELIJAH WHITE, OF MONTCLAIR, NEW JERSEY, ASSIGNOR TO CROCKER-WHEELER COMPANY, OF AMPEE, NEW JERSEY, A CORPORATION OF NEW JERSEY.

ELECTRIC SWITCH.

Application filed January 16, 1920. Serial No. 351,843.

To all whom it may concern:

Be it known that I, HAROLD ELIJAH WHITE, a citizen of the United States of America, and a resident of Montclair, in the county of Essex and State of New Jersey, have invented certain new and useful Improvements in Electric Switches, of which the following is a specification.

The object of this invention is to provide an electric switch of substantial construction for establishing and breaking electric circuits. A further object is to provide an oil-switch within a container with a hinged cover wherein the switch is carried by the cover and the parts are so organized and arranged that the container may be set against the wall and the cover lifted sufficiently to give access to the switch contacts for inspection and repair and to permit of the removal of the oil-well. A further object is to provide a suitable parallel movement for the movable contact-carrying element of the switch whereby the contacts are brought together without being inclined to each other and good contact is insured.

In the accompanying two sheets of drawings which form a part of this application—

Figure 1 is a vertical section through a container with a switch embodying this invention on the line I—II of Fig. 3, the cover being lifted.

Figure 2 is a similar section, the cover being closed.

Figure 3 is a vertical section through the container on the line III—III of Fig. 2.

Figure 4 is a vertical section through the container on the line IV—IV of Fig. 1 showing the no-voltage release magnet.

Figure 5 is a vertical section through the cover of the container on the line V—V of Fig. 3.

The invention as illustrated is embodied in a starting switch for squirrel-cage induction motors. A container 5 with a hinged cover 6 encloses the switch and accessory apparatus, and the cover is a support for the switch. The switch comprises a fixed contact-carrying element 7 in the form of a slab of insulating material which is carried within the cover between parallel bars 8, 8 which are bolted to the sides of the cover. Switch terminals in a forward row 9, a middle row 10, and a rear row 11, are carried by this slab and form the contacts of this element. A movable contact-

carrying element 12, also in the form of a slab of insulating material, carries contacts 13, 13 which may be brought into contact with either of the side rows of switch terminals and the middle row, and suitably connect them. The movable contact-carrying element is carried by two plates 14, 14, and these are each carried from the support through parallel links 15, 16. In addition there are links 17, 17 at the ends of the switch in the form of blocks mounted on a shaft 18 with a handle 19 by which the switch is operated. These links are of the same length and parallel and in triangularly disposed relation to the other links. The blocks also carry pins 20, 20 which are engaged by the ends of a coiled switch spring 21 which tends to bring the switch to an intermediate open position from either of the two closed positions.

In starting a motor with the switch, the handle is drawn forward whereby the movable element of the switch is made to connect between the contacts in the middle row and the contacts in the rear row, and circuits are closed for effecting the starting of the motor on a low voltage. Initial movement of the switch in the opposite direction is prevented by a roller 22 which is carried by one of the blocks and is obstructed by a latch prong 23. This latch prong is carried by a lever 24 which connects through a link 25 with the armature 26 of a magnet 27. The magnet has a three-pole laminated core 28 which is supported in a frame 29. The armature is fulcrumed on one corner of one of the poles and is held off from the other poles by a pair of armature springs 30, 30. Closing of the switch admits alternating current to the magnet 27 and the latch prong 23 is drawn out of the path of the roller. Having first closed the switch on the starting position, the handle can be thrown back whereby the movable element of the switch is made to connect between the contacts in the middle row and the contacts in the forward row and establish the full-speed running connections. While the magnet releases on opening the switch, the inertia of the armature and latch is sufficient to prevent the prong from moving into the path of the roller before the switch can be thrown to the running position. When the switch is thrown to the running position it is latched.

by reason of the roller coming into engagement with a second prong 31, as the blocks 17, 17 are then in the position shown in dotted lines in Fig. 2. The adjustment is such that this prong when the magnet is energized projects only slightly into the path of the roller, sufficiently to prevent the switch spring from returning the switch to open position, but not sufficiently to obstruct the manual operation of the switch.

The switch elements are submerged, when the cover is down, in an oil-well 34, which is supported in the container on a shelf 35.

Since the switch and accessory parts, which may need inspection, are located in the cover, they are at a convenient height, readily accessible and in a good light when the cover is lifted. The switch parts are in such relation to the oil-well that when withdrawn from the well by the lifting of the cover, any oil which temporarily adheres to these parts will drip back into the well and not reach any other parts of the apparatus.

It is frequently desirable to locate this apparatus against a wall where floor space is to be found which is not needed for other purposes and conductors can be more conveniently led to it, and in such a position the extent to which the cover can be thrown back is limited, but with the switch organized and proportioned as shown and operating as set forth, the oil-well can be suffi-

ciently large to permit of the operation of the switch in the submerged position, and with the cover raised to the permissible extent there is enough space for the oil-well to be lifted out to change the oil, so that a drain-cock, with the chance of leakage which it would have, need not be provided.

I claim—

1. An electric switch comprising a support, a fixed contact carrying element carried by the support, a movable contact-carrying element, and equal parallel links in a triangularly disposed relation for connecting points in fixed triangular relation on the movable contact-carrying element with points in fixed triangular relation on the support, substantially as described.

2. A double throw starting switch for electric motors with a starting and a running position and an intermediate open position, a magnet in a circuit which is closed when the switch is closed, means for preventing throw of the switch to running position which is withdrawn by the magnet when energized, means for holding the switch in running position which is held in operative position by the energized magnet, and automatic means for returning the switch to its open position.

Signed at East Orange, N. J., this 14th day of January, 1920.

HAROLD ELIJAH WHITE.
